Primary Examiner — Sheryl Lane*Assistant Examiner* — Leisha Price(74) *Attorney, Agent, or Firm* — Fraser Clemens Martin & Miller LLC; James D. Miller(57) **CLAIM**

The ornamental design for a connector, as shown and described.

DESCRIPTION

FIG. 1 is a perspective view of the connector showing our new design.

FIG. 2 is a front view thereof;

FIG. 3 is a back view thereof;

FIG. 4 is a top view thereof;

FIG. 5 is a bottom view thereof; and,

FIG. 6 is a left side view thereof.

The ornamental design which is claimed is shown in solid lines in the drawings. Any broken lines in the drawings are for illustrative purposes only and form no part of the claimed design.

1 Claim, 3 Drawing Sheets(56)
